(57) **CLAIM**

The ornamental design for an animated border for a graphical user window, as shown and described.

DESCRIPTION

FIG. 1 is a front view of the first image in the sequence for an animated border image for a display screen showing the new design;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the image sequentially transitions between the images shown in FIGS. 1–6. The process or period in which one image transitions to another forms no part of the claimed design.
